UNITED STATES PATENT OFFICE.

SARA EBERLY, OF CONTINENTAL, OHIO.

MODEL-SLIP HOLDER.

No. 833,683.

Specification of Letters Patent.

Patented Oct. 16, 1906.

Application filed February 14, 1906. Serial No. 301,076.

To all whom it may concern:

Be it known that I, SARA EBERLY, a citizen of the United States, residing at Continental, in the county of Putnam and State of Ohio, 5 have invented new and useful Improvements in Model-Slip Holders, of which the following is a specification.

This invention appertains to the art of writing, being designed most especially to 10 assist the pupil in obtaining a correct idea as to form by providing for having the model close to the writing and serving to cover the copy previously made.

The invention consists more particularly 15 of the means for holding the slip upon which the matter appears to be patterned after by the pupil, the holder being of such formation as to admit of the model-slip being easily and readily substituted by another, either by 20 being covered, by being removed, or by being interchanged with another of a pile of model-slips.

The invention contemplates a holder for 25 the model-slip which will be rigid to keep the same extended, which will be sufficiently heavy not to be readily displaced, and which will be flat to admit of the model-slip lying close to the surface, paper or slate, upon which the copies are to be written.

30 The holder consists chiefly of a plate, preferably of sheet metal, of a size to receive the model-slip, and elastic bands near the ends of the plate to confine the model-slip, said elastic bands in a modification of the invention 35 serving to prevent slipping of the holder by contact with the paper or surface upon which the device may be placed.

The invention further consists of the novel 40 features, details of construction, and combinations of the parts which hereinafter will be more fully described, illustrated, and claimed.

In the accompanying drawings, Figure 1 45 is a detail view showing the application of the invention. Fig. 2 is a perspective view of the holder, the model-slip being removed. Fig. 3 is a longitudinal section of an end portion of the holder. Fig. 4 is a detail view of the end portion of a modification. Fig. 5 is a 50 section on the line $x-x$ of Fig. 4. Fig. 6 is a section on the line $y-y$ of Fig. 4.

Corresponding and like parts are referred to in the following description and indicated in the several views of the drawings by the 55 same reference characters.

The holder 1 is oblong and flat and preferably of metal, and of a size corresponding approximately to the model-slip 2 to be confined thereon. Elastic bands 3 are provided near the ends of the holder for confining the 60 model-slip, and may be secured thereto in any manner which will admit of their substitution by others when worn or otherwise unfitted for further effective service.

The holder consists of a plate, and its end 65 portions are bent upon themselves, as shown at 4, to provide rests to elevate the holder and prevent blotting or smearing of the writing when moving the holder thereover after the completion of a line. These rests 70 or bent ends 4 also serve to prevent outward displacement of the elastic bands.

Retaining means are employed to limit the inward movement of the elastic bands as 75 well as prevent their slipping from the parts 4 when supported thereby. These retaining means consist of a shoulder 5 near each end of the plate extended across the space formed between the holder and the parts 4, said shoulders being formed by pressing portions of the plate downward, the depressions 6 thus formed constituting notches to receive the end of the finger when it is desired to engage the elastic band to stretch it, either for releasing or to make way for 80 placing the model-slip in position.

In the modification each end of the plate 1 has a retainer 7 pressed therefrom in the form of a tongue, the inner end of the tongue being reduced to form opposite spaces 8 to 90 receive the elastic band and prevents slipping thereof in either direction. The elastic band 3 encircles the plate with the exception of the portion 9, which passes over the base portion of the tongue 7. The parts of the 95 elastic at each side of the tongue are adapted to engage with the surface receiving the holder and prevent the latter from slipping.

The model-slip 2, which is usually of paper, receives any matter to be copied and is 100 placed upon the holder and retained in place by having its end portions passed beneath the elastic bands.

In practice the holder, with the model-slip 105 in position, is placed at the top of a sheet of blank paper, and the pupil copies after the model as near as possible, and after writing a line moves the holder downward so as to cover the copy and bring the model close to the writing, with the result that the eye be- 110

comes accustomed to the correct form, and the pupil in a comparatively short time acquires proficiency in patterning thereafter.

What I claim is—

- 5 1. A model-slip holder comprising a plate, elastic bands encircling the end portions of the plate and adapted to confine the model-slip, means for limiting the outward displacement of the elastic bands, and other means to limit the inward movement of said bands.
- 10 2. A model-slip holder comprising a plate having depressions near each end, elastic bands encircling the end portions of the plate for confining the model-slip, and spaced means for limiting the movement of the said elastic bands in each direction.
- 15 3. A model-slip holder comprising a plate having its end portions bent upon themselves and spaced from the body of the plate,
- 20

elastic bands encircling the end portions of the plate above the bent ends, and stop-shoulders pressed from the plate and extended across the space formed between the body thereof and its bent ends to confine the 25 elastic bands in the said spaces.

4. A device of the character described comprising a plate having portions pressed therefrom near each end to form confining means and notches, elastic bands encircling 30 opposite end portions of the plate, and a model-slip held to the plate by the elastic bands and covering the said notches thereof.

In testimony whereof I affix my signature in presence of two subscribing witnesses.

SARA EBERLY.
